R. S. C. Dougherty

ATTORNEY

UNITED STATES PATENT OFFICE

RALPH E. WILDER, OF BETHLEHEM, PENNSYLVANIA, ASSIGNOR TO BETHLEHEM STEEL COMPANY

TELLTALE MECHANISM FOR TANK CARS

Application filed January 6, 1927. Serial No. 159,299.

My invention relates to discharge valve devices for tank cars used in transporting liquids.

The object of my invention is to provide a "telltale" device which will be operated by the movement of the valve and indicate whether or not the latter is in its open or closed position.

Another object of my invention is the provision of means which will act to prevent the seating of the cover for the opening in the dome, except when the valve is completely closed.

In its broader aspects, my invention comprises a gate valve located at the bottom of the tank and operated by a handlever pivotally mounted in the dome of the tank. The handlever is operatively connected to the valve by means of a reach rod which extends beyond said lever sufficiently so that when the valve is open said rod extends above the face of the dome cover seat and prevents the seating of the cover.

The novel features of my invention will be more fully understood from the following description and claims taken with the drawings in which;

Fig. 1 is a partial longitudinal section of a tank car illustrating a valve device embodying my invention;

Fig. 2 is a plan view of the valve device;

Fig. 3 is a partial front elevation of bracket for guiding the operating lever of the device;

Fig. 4 is a partial side elevation of the reach rod of the device.

Referring to the drawing; 10 indicates the tank of car of usual construction, for carrying liquids, having a dome 11 and a removable cover 12. The tank is provided with an outlet 13 and a valve device 14 which is of the gate type preferably of the form described in my co-pending application for Letters Patent, Serial No. 105658, filed Apr. 30, 1926.

The gate 15 of the valve device 14 is connected to the lower end of the reach rod 16 which extends upwardly into the dome 11 and passes through an aperture formed in the bracket 17, which is fixed to and extends laterally from the side of the dome.

The bracket 17 functions as a guide for the

reach rod 16 and pivotally supports the operating handle 18. The reach rod is thickened as at 19 and provided at this point with an elongated opening 20 through which the operating handle extends. The bracket 17 is bent vertically upward and has an elongated slot 21 formed therein which functions as a guideway for the operating handle 18.

The slot 21 is widened at the upper end to provide the shoulders 22 for supporting the handle 18 when the latter is moved to its uppermost position as hereinafter described.

It will be noted that the major portion of the reach rod and the valve are positioned beyond the radius of the opening 23 in the dome, to give free access to the interior of the tank when the dome cover is removed. The upper end of the reach rod, beyond the thickened portion 19, is bent laterally and extends to a point within the radius of the opening 23 and, then upwardly to a position in which it is just clear of the under side of the cover 12 when the valve is in its closed position.

In operation, assuming the cover 12 to be removed, the handle 18 is raised and by virtue of its engagement with the upper end of the opening 20 causes the reach rod to lift and open the valve. In order to retain the latter in this position, the handle is moved sidewise to rest on one of the shoulders 22; the looseness of the pivotal bearing being sufficient to allow such movement. The shoulders 22 are beveled inwardly in such a manner

that gravitation tends to hold the handle against the shoulder. When the valve is in its open position, the upper end of the reach rod extends well beyond the seat of the cover 12, as shown in broken lines in Fig. 1, thus indicating clearly that the valve is in its open position and acts as warning against filling the tank. So long as the valve is incorrectly seated, the free end of the reach rod will prevent the cover from being seated and it will be necessary to close the valve completely before the cover can be fastened down.

It will be seen from the foregoing description that I have devised a "telltale" device for a tank car which is of simple and rugged construction and not liable to get out of order.

While I have shown my invention in but

one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described my invention, what I claim as new and desire to secure by Letters Patent, is:

1. In a tank car having a dome provided with an opening, the combination of a discharge valve, located beyond the radius of said opening, a removable cover for said opening, a reach rod extending upwardly to and within said dome and connected to said valve, a bracket fixed to the wall of said dome and provided with an aperture through which said reach rod extends, said reach rod provided with a thickened portion in which is formed a slot, and a handle pivoted to said bracket and extending through said slot, said reach rod being bent laterally at a point above said thickened portion and extending laterally to a point within the radius of said opening and then upwardly to a point in close proximity to said cover in its seated position, said bracket having its free end bent upwardly and provided with an elongated opening to constitute a guide for said handle, said elongated slot being widened for a portion of its length at the upper end thereof to provide a shoulder for supporting said handle when the latter is moved to its raised position.

2. In a tank car having a filling opening, the combination of a discharge valve located beyond the radius of said opening, a removable cover for said opening, an integral reach rod connected to said valve and extending upwardly and laterally to a point within the radius of said opening and then upwardly to a point in close proximity to said cover, and a handle adapted to raise said reach rod after said cover has been removed.

In testimony whereof I hereunto affix my signature.

RALPH E. WILDER.
